BEER TAPPING CONTROL MECHANISM

William Buirk, St. Bernard, Ohio

Application May 3, 1935, Serial No. 19,694

11 Claims. (Cl. 225—17)

My invention relates to a new and useful mechanism for use in connection with dispensing draught beer and provides means for regulating and controlling the pressure applied to the fluid.

Under present conditions where more than one barrel is on tap, they are usually connected to the same supply line of air or gas to create a pressure on the fluid to force the fluid up to the dispensing faucet. The carbonation of the beer in the barrels varies and the same pressure applied to more than one barrel will cause the fluid from one barrel to flow properly with the desired collar of foam while the other will be flat or cause too much foam. With my improved device, which is an improvement over my co-pending application Serial No. 693,329, the pressure can be regulated on each barrel.

The object of my invention is to provide means for automatically closing the inlet port when the pressure on the fluid reaches a predetermined point. A further object is to provide a valve in the air line to the tap which is so constructed to permit closing of the air inlet and outlet ports; or to provide an uninterrupted free passage of air through the valve; or to provide a free passage of air through the valve with a safety valve in conjunction therewith to relieve any excess pressure from being applied to the contents of the barrel, and upon operation of the safety valve, the closing of the inlet port; or to provide closing of the inlet port and maintaining a limited pressure on the contents of the barrel; or to provide closing of the inlet and safety valve ports and forming an open connection between the outlet port and a port exposed to the atmosphere to permit venting of the barrel when so desired; or to provide closing all ports except the outlet port and a by-pass port.

My invention will be further readily understood from the following description and claims and from the drawings, in which latter:

Fig. 1 is a side elevation of my improved device, shown in connection with a beer tapping mechanism, being partly broken away.

Fig. 2 is a longitudinal section view of the tap and one form of my improved control valve.

Fig. 3 is a longitudinal section view of another form of my improved control valve.

Figs. 4, 5, 6, 7 and 8 are detail sectional views, showing the various positions of the valve for accomplishing various results.

Fig. 9 is a side view of the modified valve.

Fig. 10 is a detail section of the valve, taken

in the plane of the line 10—10 of Fig. 9, and; Fig. 11 is a detail section, taken on the line 11—11 of Fig. 9.

Under the present conditions when more than one barrel is on tap, they are all connected to the same air line with a result that all barrels receive the same pressure. Due to the carbonation of the fluid one barrel will dispense with the desired foam while other barrels will dispense with too much foam or not enough foam. 10 With my improved control valve the pressure on each barrel can be controlled by providing a valve adjacent to each tap which can be set for the proper pressure on each barrel and will automatically close the inlet port when the given 15 pressure is reached, thus various pressures can be applied to any number of barrels connected to the same air line.

Beer or other beverages which are contained in barrels or casks are usually cooled by means 20 of a coil extending either through or about a suitable refrigerant whereby the beverage passing from the barrel to the dispensing faucet passes through the cool coils for serving the beverage cold. Many beverages leave deposits 25 in the coil which require periodic cleaning in order that clear untainted beverage may be served.

The cask or barrel containing the beverage is usually located either in the basement or at a 30 point below the dispensing faucet which requires a pressure to be applied to the head of the liquid for forcing the liquid up to the dispensing faucet. The usual construction now being employed for the purpose of tapping the barrel 35 comprises a tap 11 having suitable means for locking the tap to the barrel as indicated at 12. This tap has an air inlet opening 13 and a draft tube 14 extending through the tap and down into the barrel 15. The tube 14 is locked to 40 the tap as indicated at 16 for sealing the tube to the tap. A valve 17 usually inserted between the tube 14 and the coil 18, forms a connection between the coil and the tube and also permits shutting off the supply of liquid in the barrel. 45 The liquid in the barrel is forced up through the tube 14 by air pressure received through the inlet 13 and down around the tube 14 to the head of the liquid. The parts thus far described are in common usage at the present time and I 50 do not wish to confine myself to their particular construction as any suitable tapping device can be used with my improved mechanism wherein air under pressure is applied to the head of liquid in the container.

Under present conditions when more than one barrel is on tap, they are all connected to the same air line with a result that all barrels receive the same pressure. Due to the carbonation of the fluid one barrel will dispense with the desired foam while other barrels will dispense with too much foam or not enough foam. With my improved control valve the pressure on each barrel can be controlled by providing a valve adjacent to each tap which can be set for the proper pressure on each barrel and will automatically close the inlet port when the given pressure is reached, thus various pressures can be applied to any number of barrels connected to the same air line.

This control valve is indicated at 20 in Figs. 1 and 2 and comprises a housing 21 having a suitable inlet port 22 and outlet port 23. There are suitable connections on each end of the valve 20 for connecting the valve to the usual air line 24, which supplies air or gas under pressure from either a suitable compressor or a tank of carbonated gas through the valve to the tap. Extending outwardly from the air inlet port in a tubular housing 25 arranged to receive a suitable check-valve 26 therein and having threads on the outer circumference thereof for receiving a suitable coupling nut 27 for securing the air line 24 to the valve housing. A threaded portion 28 about the outer end of the outlet port is arranged to be received in a threaded projection 29 of the tap 11. A port 30 opens into the port 23 and has a safety valve 31 arranged to close the port 30 and slidably in a bore 32 and held under pressure by a spring 33 received between the valve and a threaded plug 34 which is adjustable to increase or decrease the pressure on the valve 31. A stem 35 extends upwardly from the valve and through the plug.

In the inlet opening 22 there is a cross bore 36 extending upwardly and a portion of the bore being of increased size as indicated at 37. A plug 38 is threaded in the upper end of the bore. A sliding valve 39 is received in the bore 36 and has a collar 40 slidably in the bore 37. A spring 41 of sufficient strength to lift the valve is received between the collar 40 and a shoulder 42. A passage 43 connects the bore 32 with a compression chamber 44 above the collar 40. A second passage 45 connects the passage 43 with the bore 32 above the valve 31 when the valve is in closed position. The valve 39 has an opening 46 arranged to coincide with the port 22 when the valve is open to permit a free passage of air under pressure to pass through to the port 23.

Pivoted to a lug 47 extending upwardly from the housing as at 48 is a rocker arm 49 having one end contacting with the valve stem 35 and the other end contacting an upwardly extending stem 50 of the valve 39. The upper end of this stem has flat faces 51 received between depending lugs 52 on the rocker arm to prevent the valve 39 from rotating. This rocker arm aids in operating the shut off valve and can be used without the air pressure and acts as a fulcrum.

In the operation of my improved valve and assuming a pressure of twenty pounds is supplied from the main air line and it is desired to have twelve pounds of pressure on one barrel and sixteen pounds on the other barrel, the safety valve is set on each barrel for the given pressure by adjusting the plug 34. As soon as the pressure in the barrels reaches the given pressure the valve 31 will raise permitting the pressure to escape through the passage 43 to the chamber 44

forcing the collar 40 down for closing the inlet port 22. This action is aided by the rocker arm for making the action positive. If through the carbonation of the fluid in the barrel the pressure increases, the valve 31 will raise still higher to open the vent 53 permitting the excess pressure to escape to the atmosphere. As the valve 39 moves down the air trapped there below escapes through a small opening 54 in the base of the bore 36, and an opening 55 below the collar 40. When the pressure in the barrel is reduced through the drawing of fluid therefrom or otherwise, the valve 31 closes, opening the passage 45 permitting the air in the chamber 44 to escape and the cut-off valve will raise to the position shown in Fig. 2, opening the inlet port 22.

In the device shown in Figs. 3 to 11 inclusive I have incorporated my improved control valve with the valve set forth in my co-pending application heretofore referred to. In this construction like parts are indicated by similar reference numeral raised to the series 100.

Under present conditions when it is desired to clean the coil, the air to the opening 13 is shut off and the valve 17 closed to prevent the liquid from passing up through the tubes, but considerable liquid remains in the coil which is often 75 or 100 feet in length, and when disconnected from the valve 17 is drained from the coil and is usually a complete loss to the proprietor. With my improved form of valve, the liquid in the coil can be returned to the barrel by setting the valve to the position shown in Fig. 8 whereby the pressure on the fluid in the barrel escapes; or the valve may be set to a position as shown in Fig. 3 whereby all the ports will be closed, thus preventing pressure being applied to the liquid; or the valve may be set to a position as shown in Fig. 4, whereby the air will by-pass the automatic shut off mechanism; or the valve may be set to a position as shown in Fig. 5, whereby the air has a direct passage through the valve; or the valve may be set to a position as shown in Fig. 6 which places the automatic shut off mechanism in operative position; or the valve may be set to a position as shown in Fig. 7 whereby the incoming air is shut off with the safety valve connected to the port leading to the barrel to relieve excessive pressure on the liquid.

The valve housing 121 is provided with a tapered bore 60 in which a valve 61 is received and held therein by means of a nut 62 received over a threaded end 63 of the plug. The plug is provided with suitable openings 64, 65 and 66, all of these openings being interconnected for permitting air to pass from one opening to the other, depending on the position of the valve. The valve housing is provided with a plurality of ports having a main inlet port 122, an outlet port 123, a relief port 67 to the atmosphere, a port 130 to the safety valve and a by-pass port 68. The valve plug is turned to the desired position by means of a handle 69 secured to the plug and having a pointer 70 integral therewith and arranged to indicate the position of valve by registering with suitable marks on the valve housing indicated at 71, 72, 73, 74, 75 and 76.

Thus in the operation of this valve when the valve plug is in the position shown in Fig. 3 and the pointer 70 registering with the mark 72 all of the ports in the housing will be closed for preventing air under pressure to escape from the port 123. In the event it is desired to omit the use of the automatic shut off means, the

valve is turned to the position shown in Fig. 4 with the pointer 70 registering with the mark 71, and in this position the port 65 will register with the outlet port 123 and the port 64 will register with the by-pass port for permitting the air coming into the valve to pass into the by-pass passage 77 through the valve plug to the tap; or, it may be desired to pass the air through the inlet port 122 through port 66 and out of the port 64 to the outlet port 123, such arrangement is shown in Fig. 5 in which case the pointer 70 will register with the mark 73; or, it may be desired to use the safety device and automatic shut off valve, in which case the valve plug is turned with the pointer 70 registering with the mark 74. In this position the port 64 will register with the port 123, the port 65 registering with the port 130 and the port 66 registering with the port 122, as shown in Fig. 6. This arrangement is used when more than one barrel of beer has connections with a single air supply source and it is desired to regulate the pressure applied to the respective barrels. Thus the valve plug 135 can be set to a given pressure as indicated on a gauge 78 and when the pressure on the fluid in the barrel reaches the limit to which the valve 131 is set it will cause the valve to raise for permitting the air to pass through the port 143 for aiding in closing the valve 139 for shutting off the air pressure to the barrel. After a certain quantity of the liquid is drawn from the barrel and the pressure thereon decreased, the valve 131 will again close, opening the valve 139.

In cases where the fluid in the barrel is of such a nature due to chemical reactions therein, causing it to build up a pressure of its own, and it is desired to set the valve so that this pressure may be relieved before it becomes excessive to cause damage to the equipment, the valve can be set to a position as shown in Fig. 7 wherein the pointer 70 registering with the mark 75 and the port 64 registering with the outlet port 123 and the port 65 registering with the safety valve port 130.

When it is desired to clean the coils the valve may be set to the position shown in Fig. 8 in which position the pointer 70 will register with the mark 76 and the port 64 will connect the ports 123 and 67 whereby the air under pressure in the barrel can escape to the atmosphere for relieving the pressure on the fluid, thus permitting the fluid in the coil to drain back into the barrel. The coil can then be disconnected from the valve 17 and cleaned without the loss of any of the beverage.

The valves 39 and 139 may be used as shutoff valves by merely pushing downwardly on the stems 50 and 150 to release the flats 51 and 151 from the lugs 52 and 152, and turning the valves a half turn to close the ports 22 and 122.

It will be apparent from the foregoing description that I have devised a valve construction that overcomes many defects in the present system of dispensing fluid and while I have shown the preferred form of the same, I do not wish to restrict myself to any specific details beyond that required by the scope of the appended claims.

Having thus fully described my invention, what I claim as new and desire to secure by Letters Patent, is:

1. A beer tapping control mechanism comprising a housing, an air passage through said housing, an adjustable safety valve in said hous-

ing having a port connecting with said passageway, and means controlled by said air through said safety valve for closing said passage.

2. A beer tapping control mechanism comprising a housing, a passageway through said housing, a safety valve in said housing having a port connecting with said passage, a second valve in said passage and means interconnecting said valves whereby operation of said safety valve actuates said second valve.

3. A beer tapping control mechanism comprising a housing, a passageway through said housing, a safety valve in said housing having a port connecting with said passageway, a pressure valve in said housing for closing said passageway, a port connecting said safety valve with said pressure valve whereby upon raising of said safety valve said air under pressure will operate said pressure valve for closing said passageway.

4. A beer tapping control mechanism comprising a housing, a passageway through said housing, a safety valve having a port connecting with said passageway, a pressure valve in said housing for closing said passageway, a port connecting said safety valve with said pressure valve whereby upon raising of said safety valve the air under pressure will operate said pressure valve for closing said passage, and means for returning said valves to normal position upon reduction of pressure in said passageway.

5. A beer tapping control mechanism comprising a housing, a passage through said housing, a safety valve having a port connecting with said passage, a pressure valve in said housing for closing said passage, a port connecting said safety valve with said pressure valve whereby upon raising of said safety valve the air under pressure will operate said pressure valve for closing said passage, and a rocker arm having contact with said valves.

6. A beer tapping control mechanism comprising a housing, a passage through said housing, a safety valve having a port connecting with said passage, a shut off valve in said housing for closing said passage, a rocker arm connecting said valves whereby upon raising of said safety valve said shut off valve will close said passage.

7. A beer tapping control mechanism comprising a housing, a passage through said housing, a safety valve having a port connecting with said passage, a shut off valve in said housing for closing said passage, a rocker arm connecting said valves whereby upon raising of said safety valve said shut off valve will close said passage and means for returning said valves to normal position upon reduction of pressure in said passage.

8. In a beer tapping control mechanism the combination of a housing, a valve in said housing comprising a plug having a plurality of connected openings, a plurality of ports in said housing comprising an inlet and outlet port and safety valve port about said valve plug, said safety valve port provided with a safety valve and means operable through the action of said safety valve for closing said intake port.

9. In a beer tapping control mechanism the combination of a housing, a valve in said housing comprising a plug having a plurality of connected openings, a plurality of ports in said housing about said valve plug comprising an inlet and outlet port, another port provided with a safety valve, a valve in said inlet port and means operable through the action of said safety valve for closing said intake port valve.

10. In a beer tapping control mechanism the combination of a housing, a valve in said housing, a central opening through said housing, a valve plug in said central opening, having a plurality of connected openings, a plurality of ports in said housing about said valve plug, one of said ports open to the atmosphere, another port provided with a safety valve, one of said ports being an intake port, a valve in said intake port operable through the action of said safety valve.
- 5 11. In a beer tapping control mechanism the combination of a housing, a central opening through said housing, a valve plug in said central openings, a plurality of ports in said housing about said valve plug, comprising an inlet and outlet port, a port open to the atmosphere, a safety valve port and a by-pass port, a safety valve in said safety valve port, a shut off valve in said intake port operable through the action of said safety valve.

WILLIAM BUIRK.
